UNITED STATES PATENT OFFICE.

PHILIP FRANK VOGT, OF DAYTON, OHIO.

BOILER-FLUE CLEANER.

SPECIFICATION forming part of Letters Patent No. 767,854, dated August 16, 1904.

Application filed September 2, 1903. Serial No. 171,659. (No model.)

To all whom it may concern:

Be it known that I, PHILIP FRANK VOGT, a citizen of the United States, residing at Dayton, in the county of Montgomery and State 5 of Ohio, have invented new and useful Improvements in Boiler-Flue Cleaners, of which the following is a specification.

This invention relates to boiler-flue cleaners or scrapers of that class embodying a central stem and longitudinal toggle arms or links pivotally connected at their free ends to blades movable in relation to the stem and held in position by a spring, whereby the arms and the blades are yieldingly held in expanded position.

The primary object of the invention is to provide a simple and effective organization of elements whereby the spring is protected by an inclosure positioned within the planes of 20 the blades, the said inclosure having a terminal element to engage the inner portions of the heads of the blades to cause a more positive adjustment of the latter and their retention in adjusted or expanded position.

A further object of the invention is to connect the scraper or toggle-arms with the heads of the cleaner without the use of bolts or rivets and without requiring machine-work, so as to simplify the construction of the device 25 and reduce the cost of its manufacture and also to movably articulate or assemble the toggle-arms and blades by means of removable devices which will permit ready separation of all the parts should it become necessary to disorganize them for different purposes, such as repair or to replace one of the parts that may have become broken.

With these and other objects and advantages in view the invention consists in the 40 construction and arrangement of the several parts, which will be more fully hereinafter described and claimed.

In the drawings, Figure 1 is an elevation of a cleaner embodying the features of the invention. Fig. 2 is a transverse vertical section through the same.

Similar numerals of reference are employed to indicate corresponding parts in the views.

The numeral 1 designates a series of blades 45 having inclined scraping edges 2, lower bi-

furcated terminals 3, and upwardly-projecting shanks 4. The blades in the present instance are four in number and are disposed in opposite pairs surrounding the center of the cleaner. The blades have inward extensions 55 5, with upper concaved faces 6, for a purpose which will be presently set forth. Pivotally and detachably secured to the lower bifurcated terminals 3 of the blades are the upper ends of toggle-arms 7, cotter-pins 8 being preferably 60 employed to connect the said toggle-arms to the blades, so that they may be readily withdrawn to separate the connected parts. The lower ends of the arms 7 and the upper ends of the shanks 4 are formed with recesses 9, opening 65 outwardly therefrom to loosely bear on bars 10, located at the inner ends of heads 11 and 12. The portions of the lower extremities of the arms 7 and the upper extremities of the shanks 4 inward from the recesses 9 are rounded or 70 of convex form, as at 13, and the heads 11 and 12 at points outward from the bars 10 are recessed or cut away, as at 14, to permit the said lower ends of the arms and upper extremities of the shanks to have un retarded 75 movement during the expansion and contraction of the blades and the corresponding movement of the arms 7. Each head is formed with a central sleeve 15, and extending longitudinally through the said sleeves are the two 80 members 16 and 17 of the stem, which are operatively joined at an intermediate point, as will be now set forth. The member 17 of the stem, which projects through the sleeve 15 of the head 12, may be said to be the "handle" 85 portion of the stem and will be made up of a series of connected sections, as many of said sections being added as are required to operate throughout the full length of flue-tubes or flues of different lengths, and the exterior 90 surfaces of the contiguous ends of the several sections are screw-threaded and have sleeves 18 run thereover. The front terminal of the member 17 is secured to the rear head 19 of a central cylindrical closure 20, having a head 95 21 at its opposite end formed with a projecting flange 22, said head 21 having a central opening 23, in which the rear extremity of the member 16 of the stem has sliding movement. This rear extremity of the member 16 100

of the stem extends into the cylindrical closure 20 and is terminally formed with a flange 24 to provide a pressure-seat for one terminal of a spring 25, mounted in the closure 20 5 and having its opposite end or terminal bearing against the inner surface of the head 21. The flange 24 also normally abuts against the inner surface of the rear head 19. The flange 22 of the head 21 has a convex edge 26, which 10 contacts or engages with the concave edges or faces 6 of the extensions 5 on the scraper-blades, and by such engagement of the flange 22 with the extensions of the scraper-blades 15 the inward and outward movement of the latter is rendered more positive. Moreover, by disposing the central cylindrical closure or spring-barrel 20 in the manner set forth and projecting the flange 22 the scraper-blades are at all times held in contact with the said flange 20 through the medium of the faces 6, and these parts are shielded by the heads of the blades, and soot or other accumulations loosened by the cleaner is prevented from passing through the latter.

25 The forward extremity of the member 16 of the stem, which projects through the sleeve 15 of the head 11, is formed with screw-threads 27 and engaged by an adjusting-nut 28 and clamping-nut 29. Through the medium of 30 these nuts and the screw-threaded extremity or terminal of the member 15, just explained, the expansion of the scraper-blades and the toggle-arms is regulated, and likewise the tension of the spring 25 can be controlled to set 35 up a stiff binding action on the edges 1 of the blades with the interior surfaces of the flues or other orifices into which the device may be inserted. It will be seen that through the use of the spring 25 the scraping edges of the 40 blades have a yielding contact with the interior surfaces of the flues or orifices and by protecting or inclosing the several parts, as heretofore referred to, and preventing soot from lodging thereon interference with the action 45 of the spring will be prevented and a positive adjustment of the scraping-blades may be obtained. Furthermore, by locating the inclosure 20 as stated it is less liable to become broken during the use of the cleaner and the 50 opposite extremities of the heads 11 and 12 are freed of unnecessary projecting devices adjacent thereto and engaging the stem members.

If found necessary at any time, the scraper-blades, as well as the toggle-arms, may be disconnected or detached, and, furthermore, for 55 convenience in assembling the parts of the stem and the closure 20 the head 19 is made

removable through the provision of screw-threads thereon and on the interior of the end of said closure which the head engages.

Having thus fully described the invention, what is claimed as new is—

1. In a flue-cleaner of the class set forth, the combination with heads of cleaning-blades having their ends movably attached thereto, and toggle-arms having their inner ends movably connected to the blades and their outer ends also movably supported, of stem members extending longitudinally through the central space between the blades, a closure for connecting said members, the end of one of said members being attached to the closure and an end of the other member freely movable in said closure, and a spring mounted in the said closure. 75

2. In a flue-cleaner, the combination of expandable blades, toggle-arms detachably secured to said blades, end heads to which said blades and arms are detachably secured, a stem, comprising separate members projecting through the said heads, the heads being free to slide on the stem members, a cylindrical closure located in the central space between the blades and having a flange at one end to engage portions of said blades, one stem member being fixed to the closure and the other having its inner end slidable in said closure, and a spring surrounding the end of the stem slidable in the closure and operating to return the parts to normal position. 85

3. In a flue-cleaner, the combination with expandable cleaning-blades, of stem members longitudinally extending through the space between the said blades, heads on the stem members to which the blades are connected, a cylindrical closure also disposed in longitudinal position on the stem members between the blades and to one end of which one of the members is fixed, the other member being slidable within the closure and the latter having a flange at one end to engage inner portions of the blades, a spring within the closure, and adjusting means on the outer terminal of the spring member which movably passes into the closure, the said closure being located centrally 100 between the blades and fully shielding the spring therein. 105

In testimony whereof I affix my signature in presence of two witnesses.

PHILIP FRANK VOGT.
